UNITED STATES PATENT OFFICE.

FRANK A. WEBB, OF PROTECTION, KANSAS.

ACETYLENE-GAS GENERATOR.

1,228,998.

Specification of Letters Patent.

Patented June 5, 1917.

Application filed April 29, 1915. Serial No. 22,631.

To all whom it may concern:

Be it known that I, FRANK A. WEBB, a citizen of the United States, residing at Protection, in the county of Comanche and 5 State of Kansas, have invented certain new and useful Improvements in Acetylene-Gas Generators; and I do hereby declare the following to be a full, clear, and exact description of the invention, such as will enable others skilled in the art to which it appertains to make and use the same.

The invention relates to improvements in acetylene gas generators.

The object of the present invention is to 15 improve the construction of acetylene gas generators and to provide a simple, practical, and comparatively inexpensive acetylene gas generator equipped with a valve for automatically controlling the discharge of 20 the carbid from the carbid holder adapted to be operated by the bell or receiver when the gas therein is nearly consumed.

A further object of the invention is to 25 provide an automatic controlling valve adapted to accurately discharge the desired amount of carbid into the water tank and capable of effectively preventing more than a single charge being delivered at one time and of preventing any pinching of the car- 30 bid in its operation so that the free discharge of the carbid will be assured.

A further object of the invention is to 35 provide an acetylene gas generator which will be perfectly safe and reliable and not require an automatic relief or safety blow off valve.

Furthermore it is the object of the invention to provide an acetylene gas generator adapted to be easily cleaned so that 40 a sludge mixer or agitator for stirring the water will be unnecessary.

With these and other objects in view the invention consists in the construction and novel combination and arrangement of parts 45 hereinafter fully described, illustrated in the accompanying drawings and pointed out in the claims hereto appended, it being understood that various changes in the form, proportion and minor details of construction 50 may be resorted to without departing from

the spirit or sacrificing any of the advantages of the invention.

In the drawings

Figure 1 is a vertical sectional view of an acetylene gas generator constructed in accordance with this invention,

Fig. 2 is an enlarged sectional view of the automatic carbid dumping and controlling valve,

Fig. 3 is a rear elevation of the same, 60

Fig. 4 is a top view of the carbid holder.

In the accompanying drawings in which is illustrated the preferred embodiment of the invention, 1 designates a water tank of any desired construction and capacity provided at the top with a central opening 2 and having upwardly extending spaced concentric walls or shells 3 and 4 surrounding the opening and forming a water seal 5 into which a bell or floating receiver 6 extends. The inner wall or shell 3 supports a carbid holder 7 provided at its upper portion with outwardly extending hooks 8 which engage over the upper edge of the inner shell or wall 3 of the water seal, 75 whereby the carbid holder is removably supported in position over the water in the tank 1. The tank 1 is provided at the bottom with a sludge valve 9 and the bell 6 is provided at the top with a flared aperture 80

10 and a removable screw cap adapted to be taken off to permit the bell to be readily lifted out of the water seal when it is desired to fill the carbid holder 7, by removal of the screw cap a pressure in the valve and 85

the atmospheric pressure are equalized thereby allowing the same to be easily removed. The carbid holder which has a tapered lower portion 12 is provided at the top with a filling opening 13 which is normally covered by a pivoted closure 14 but any suitable closure may of course be employed as the filling opening of the carbid holder is located within the bell 6. 90

The tapered lower portion 12 of the carbid holder has flattened walls which are inclined downwardly, and it is provided with a bottom outlet 13 preferably formed by cutting away one of the walls of the lower portion 12 but the said outlet 13 may be formed in 100

any other desired manner. The walls at the side of the outlet 13 and the wall at the opposite end of the outlet 13 are closed or imperforate and the carbid holder is provided at the bottom of the outlet with a transverse pindle 14 which pivots a controlling and dumping valve 15 to the carbid holder. The valve 15 is composed of spaced sides and a connecting bottom portion which is extended at the back to form an upwardly curved rear wall 16. The pindle 14 extends through the side walls of the carbid dumping and controlling valve which valve has a tapered portion 17 projecting in advance of the transverse pindle 14 and forming a discharge mouth or spout. The valve 15 which extends downwardly and rearwardly at an inclination as illustrated in Fig. 1 of the drawings when in its non-feeding position is provided with a plate or partition 18 fixed to the side walls of the valve and extending across the same in parallelism with the bottom of the valve.

The plate 18 which extends rearwardly from the transverse pindle forms a closure for the outlet of the carbid holder and is adapted to be swung upwardly to the dotted position illustrated in Fig. 2 of the drawings to cut off the flow of the carbid from the carbid holder into the valve when the valve is moved to its dumping position. The carbid controlling and dumping valve is also provided with a rear hinged section or wall 19 consisting of a plate connected at its lower edge to the rear wall 16 by a transverse pindle 20 and extending entirely across the space between the sides of the valve and extending upwardly from the rear wall 16 in a perpendicular position which is maintained by the rear hinged wall section or member 19 during the opening and closing movement of the valve, and fear of the carbid from being forced outwardly over the rear wall of the dumping valve during the movement of the dumping valve will be entirely eliminated. When the valve is being dumped the rear hinged plate or member 19 moves away from the carbid holder, the plate 19 moves backward leaving the carbid and freeing the same within the valve and permitting a free discharge of the carbid from the valve. When the valve is returned to its closed position the hinged rear plate or member 19 regains its initial position as the carbid refills the valve. The carbid controlling and dumping valve is automatically operated by the bell 6 which is adapted to engage a roller 21 mounted on one end of a lever 22 in a fork or bifurcation thereof and it is adapted to ride against the inner face of the top of the bell 6 which in moving downwardly through the consumption of the gas contained within it is adapted to oscillate the lever 22, swinging one arm downwardly and raising the other arm of the

lever 22. The lever 22 is pivoted intermediate of its ends to a projecting support 23 which extends upwardly from the top of the carbid holder and the pivot of the lever 22 is located at a point between the center and one end of the lever, the short arm of the lever being connected to the upper end of a rod 24 which extends through the carbid holder. The carbid holder is provided with a vertical tube 25 which extends from the bottom to the top of the carbid holder and in which the rod 24 is freely movable. The lower end of the rod 24 is provided with a fork 26 for connecting the rod with the carbid controlling and dumping valve. The sides of the fork or bail are provided at their lower terminals with inwardly projecting pivot portions 27 which engage perforations of ears 28 secured to the exterior of the valve 15 at the sides thereof and having the perforations located in the rear edge of the transverse plate or partition 18. The rod 24 is connected with the wall section or plate 19 by a link 29 of approximately U-shape, the transverse connecting portion passing through an eye 30 of the said wall section or plate 19. The wall section or plate 19 is provided at its upper edge with the said eye 30 and the sides of the link 29 are provided with eyes 31 which receive the transverse portions of the fork or bail 26 whereby the link 29 is hinged to the same. The rod 24 is vertically movable and the link connection between the same and the plate or wall section 19 maintains the latter in a perpendicular position throughout its upward and downward movement.

The vertical tube 25 is of sufficient diameter to permit the necessary play of the connecting rod 24 in the opening and closing movement of the valve. The acetylene gas generator is equipped with a filter 32 mounted upon the tank 1 at one side of the water seal and comprising a cylindrical casing, a series of frusto-conical baffle plates 33 and filtering material 34 located within the upper end of the casing above the baffle plates. The filtering material may consist of pack felt, wool or any other suitable material and it is adapted to remove any of the sediment of the ash from the gas before the same enters the gas pipe 35. The lower portion of the casing of the filter contains water, the level of which is maintained constant by an overflow pipe 36 mounted on the tank and extending into the filter and depending into the said tank below the surface of the water contained within the tank. The gas to be cleaned or filtered passes into the casing of the filter through a gas inlet pipe 37 secured at its lower end to the tank and located above the surface of the water within the same and provided at the top with a return bend 38 and having a depending leg 39 extending into the water of the filter. The depending leg 39 of

the gas inlet pipe is provided with submerged perforations preferably about one-sixteenth of an inch in diameter and adapted to permit the gas to escape from the inlet pipe and bubble through the water. The depending portion or leg 39 also carries a funnel-shape deflector and separator 41 presenting inclined sides to the bubbles of gas and adapted to cause the same to rise in a separated condition to the surface of the water within the filter. The baffle plates which are adapted to dry the gas and remove the water therefrom are provided with openings 42 and 43 alternately arranged at the center and sides 15 of the baffle plates and adapted to cause the gas to pass over the said plates. The filtering material removes all the ash from the gas and the pipe 35 which receives the clean gas is connected with a pipe 44 leading to 20 the lights or other means of consumption of the gas, a stop cock 45 being provided for cutting out the pipe 44 to prevent any air entering the same when refilling the carbid holder. A gas pipe 35 is also connected with 25 a vent pipe 46 having a cut out cock 47 and adapted to permit the escape of air from the acetylene gas generator after the carbid holder has been refilled. A drain pipe 48 extends downwardly from the pipe 44 to a 30 point below the surface of water within the tank to permit any water of condensation to find its way back into the tank should it pass beyond the filter. The filter is provided at the bottom with a drain plug 49 and it 35 has a filling tube 50 depending from the top of the filter and extending through the baffle plates and provided with a closure plug 51 at its upper end. This will enable the water and sediment to be drawn off from 40 the filter and clean water placed therein. Should the water through accumulation of sediment within the filter rise above the upper end of the overflow pipe 9 it will flow into the water tank and a constant level of 45 the water within the filter will be maintained.

In order to return the valve of the carbid holder to its closed position, the said valve is provided with a weight 52 of any desired 50 construction mounted upon the rear portion of the valve at the bottom thereof and adapted to positively close the said valve after the contents have been discharged and the operating mechanism released by the 55 raising of the bell. The acetylene gas generator operates in the usual manner to produce the gas and the gas accumulates within the bell which operates the valve opening mechanism when the gas within the bell is 60 nearly consumed and the gas produced by a fresh charge of carbid operates to lift the bell and release the valve and permit the same to close.

It will be seen that the acetylene gas generator is easily cleaned, that the carbid con-

trolling and discharging valve and the operating mechanism therefor are located below the bell or receiver and that it is impossible to discharge more than one charge of carbid into the water tank at each operation of the valve and that the operation of the valve is entirely automatic through the bell or receiver so that it is impossible to manufacture gas until the gas within the receiver is nearly consumed and the receiver 70 permitted to descend and operate the valve opening mechanism.

What is claimed is: —

1. An acetylene gas generator including a carbid holder having an outlet in one of its sides near its lower end, a valve located below the lower end of said holder and extending in two directions beyond said side and having a receiving and a discharging end, means establishing a pivotal connection between said valve and holder at a point to one side of said outlet, said valve normally occupying an inclined position with its receiving end lowermost and on that side of the holder in which the outlet is located, means for raising said receiving end in the direction of said side of the holder to discharge the contents of the valve, a plate carried by said valve for cutting off the supply of carbid when said valve is in discharging position, a vertical rear wall hinged at its lower end to the receiving end of the valve, and means for supporting the upper end of said wall and for holding said wall against movement bodily in the direction of said side of the holder during the movement of the valve into discharging position whereby to prevent the packing of the carbid between said rear wall, said side of the holder and said plate so as to insure a free and complete discharge of the carbid from the valve. 95

2. An acetylene gas generator including a carbid holder having an outlet in one of its sides near its lower end, a valve located below the lower end of said holder and extending in two directions beyond said side and having a receiving and a discharging end, means establishing a pivotal connection between said valve and holder at a point to one side of said outlet, said valve normally occupying an inclined position with its receiving end lowermost and on that side of the holder in which the outlet is located, means for raising said receiving end in the direction of said side of the holder to discharge the contents of the valve, a plate carried by said valve for shutting off the supply of carbid when said valve is in discharging position, a vertical rear wall hinged at its lower end to the receiving end of said valve, and means connected to said raising means and to the upper end of said rear wall, said last 110 115 120 125 130

named means supporting the upper end of said wall and holding said wall against movement bodily in the direction of said side of the holder during the movement of 5 the valve into discharging position, whereby to prevent the packing of carbid between said rear wall, said side of the holder and said plate so as to insure a free

and complete discharge of the carbid from the valve.

In testimony whereof I affix my signature in presence of two witnesses.

FRANK A. WEBB.
